UNITED STATES PATENT OFFICE.

ALVA W. B. JOHNSON, OF BIRMINGHAM, ALABAMA.

SELF-SERVICE STORE.

1,380,968.

Specification of Letters Patent.

Patented June 7, 1921.

Application filed April 8, 1918. Serial No. 227,280.

To all whom it may concern:

Be it known that I, ALVA W. B. JOHNSON, a citizen of the United States, and a resident of Birmingham, in the county of 5 Jefferson and State of Alabama, have invented a new and Improved Self-Service Store, of which the following is a full, clear, and exact description.

My invention has for its object to provide 10 a self-service store with a plurality of compartments for the display and sale of separate lines of stock, the compartments having corner wrapping, checking and paying stations so that the clerks who are on duty 15 at the said stations may be in close proximity to the customers in one or more compartments and may, at the same time, watch the entrances and exits.

Another object of the invention is to provide 20 a plurality of compartments disposed side by side and end to end, the compartments having entrances and exits at their outer side walls so arranged that customers will be obliged after entering a compartment 25 to walk through the compartment before passing therefrom. There are also exits at the rear of the compartments which permit customers to pass from the forward compartments to the rear compartments but 30 which prevent the customers from walking directly from a rear compartment to a forward compartment.

Additional objects of the invention will appear in the following specification in 35 which the preferred form of my invention is described.

In the drawings, similar reference characters refer to similar parts in all the views, in which—

40 Figure 1 is a sectional plan view showing one method of arranging my self-service store according to the peculiar size and plan of the floor covered, but it must be understood that my invention is intended to cover 45 the assembling of compartments arranged and disposed of end to end and side to side with corner wrapping, paying and watching stations to meet the requirements of any size floor or plan wherein two or more divisions or compartments are required.

Fig. 2 is a fragmentary sectional plan view of the self-service store illustrated on an enlarged scale;

Fig. 3 is a sectional elevation of Fig. 2;

55 Fig. 4 is a sectional fragmentary view illustrating the manner in which the coun-

ters are arranged, but it must be understood that counters or tables can be arranged in each compartment in any desired manner, and I do not want to restrict myself to the 60 exclusive counter arrangement as shown by Fig. 4.

Fig. 5 is a view illustrating the construction of certain of the turnstiles which permit customers to pass through in one direction 65 but which prevent customers walking in the opposite direction.

By referring to Fig. 1 of the drawings, it will be seen that the store is provided with two aisles 10 and 11, each having a 70 main entrance 12. At each side of each aisle, there are sets of compartments which are numbered 13, 14, 15, 16, 17, 18, 19, 20, 21, 22, 23, 24, 25, 26, 27 and 28. It will be understood that while two aisles are 75 shown in Fig. 1 of the drawings, this plan applies to the peculiar size and shape of the floor illustrated and that other arrangements are within the scope of the invention.

It will be seen that the compartments 14 80 and 15 are disposed side by side between the aisles 10 and 11, and that the compartments 18 and 19, compartments 22, 23 and the compartments 26, 27 are positioned in the rear of each other and between the said 85 aisles 10 and 11. The remainder of the compartments are disposed at the outer sides of the aisles 10 and 11. At the forward ends of the compartments 13, 14, 15 and 16 and adjacent the main entrances 12, there are 90 entrances from the aisles 10 and 11 which are numbered 29, 30, 31 and 32. At the rear of the last mentioned compartments and leading to the aisles 10 and 11, there are exits 33, 34, 35, 36.

95 The compartments 17, 18, 19 and 20 are provided with similar entrances 37, 38, 39 and 40 which are positioned at their forward ends and adjacent the exits 33, 34, 35 and 36. At the rear of the compartments 17, 18, 19 and 20, there are exits 41, 42, 43, and 44 which lead from the rear of the last mentioned compartments to the aisles.

The remainder of the compartments in the rear of the last mentioned compartments 100 are provided with entrances and exits similar to the entrances and exits with which the compartments 17, 18, 19 and 20 are provided.

105 The rear of the compartments 14, 15 110 which are disposed side by side between the walls 10 and 11, are connected by a lateral

passage 45. The rear of the compartments 18 and 19 are connected by a similar lateral passage 45, and in a similar manner the compartments 22 and 23, 26 and 27 are connected by lateral passages 45. The rear of the compartments 14 and 15 are also connected with the forward ends of the compartments 18 and 19 by exits 46 which lead from the compartments 14 and 15 to the compartments 18 and 19. These exits 46 are disposed at the junction of the exits and entrances 34, 38 and 35, 39 and also at the lateral passage 45 which connects the rear of the compartments 14 and 15.

15 A watching, checking and paying station 47 is disposed at the junction of the exit 35, the entrance 39 and one of the exits 46. A watch checking and paying station 48 is disposed at the junction of the lateral passage 20 45 and two of the exits 46, and a watching checking and paying station 49 is disposed at the junction of the exit 34, the entrance 38 and an exit 46.

Exits 50 lead from the rear of the compartments 18 and 19 to the forward ends of the compartments 22 and 23, and there is a watching checking and paying station 51 at the junction of the exit 43, the entrance 39 and one of the exits 50. There is a watching checking and paying station at the junction of the lateral passage 45, with two of the exits 50, and there is a watching checking and paying station 53 at the junction of the exit 42, the entrance 38 and one of the 35 exits 50. There are also watching stations 54 at the junction of the forward ends of the compartments 14 and 15 with the main entrances 12.

The entrances 30, 31 and 38, 39 are provided with turnstiles 55 which permit customers to enter the forward ends of the compartments from the aisles 10 and 11, but which prevent customers from leaving the compartments at the said entrances. The 45 exits 34, 35, and 42, 43 are also provided with turnstiles which are numbered 56 and which prevent customers from entering the compartments through the said passages while permitting customers to pass from the 50 compartments to the aisles 10 and 11 through the said passages.

The exits 46 and 50 are provided with turnstiles 57 which permit customers to pass from the forward to the rear compartments 55 while preventing customers from passing from the rear to the forward compartments. It will be seen that with this arrangement, it will be necessary for customers to enter the forward ends of every compartment 60 which is to be visited and pass from the rear of the compartment, although it is only necessary for the customer to enter the compartment in which he desires to purchase merchandise.

65 The lateral passages 45 are preferably

provided with turnstiles 58 but these turnstiles 58 permit customers to pass in either direction.

As watchers and checkers are positioned at the stations 54, 47, 48, 49, 51, 52 and 53, 70 it will be possible for the watchers and checkers at all times to furnish the customers with any desired information with reference to the counter in which the desired merchandise may be found, and it will also 75 be possible for the watchers and checkers to watch the customers to prevent theft and to wrap packages as the customers leave the compartments, and collect the purchase price.

80 It will be seen that the compartments 13, 16, 17, 20, 21 and 24 are disposed behind each other but that they are not disposed side by side and, therefore, the lateral passages are not necessary. However, in other respects the arrangement of the last mentioned compartments is similar to the arrangement of the compartments which are disposed between the aisles 10 and 11.

85 The merchandise in the compartments is 90 exhibited on counters 59 which are preferably constructed as best illustrated in Fig. 4 of the drawings with a glass panel 60 at the rear of the counter, the glass panel 60 dividing the counters in adjacent compartments. 95

In Fig. 5 there is shown the form of turnstile which I prefer to use at the entrances 29, 30, 31, 32, 37, 38, 39, 40, etc. Similar turnstiles are used at the exits 33, 34, 35, 36, 41, 42, 43, 44, 46, etc. This turnstile has a 100 shaft 61 secured to the base 62, a gear 63 being secured to the shaft 61, which is covered by a cap 64 which is also secured to the shaft 61. A drum 65 is rotatably mounted on the shaft 61 below the cap 64, and pivoted to the top of the drum 65 there is a two armed pawl 66. Below one of the arms 67 of the turnstile there is a cylindrical member 68 having an outer head 69 and within the cylindrical member there is a 110 spring 70, the spring being adjustable so that it may press against the pawl 66 adjacent either of its arms which permits a reversal of the possible movement of the turnstile when desired.

115 Having thus described my invention, I claim as new and desire to secure by Letters Patent:

1. In an apparatus for vending merchandise, two compartments, each having its respective entrance and exit passageway, and the two compartments having a communicating passageway, means to prevent the use of said entrance passageways as exits, said communicating passageway being juxtaposed to the exit passageways from both compartments, and a service station common to all said exit and communicating passageways.

2. In an apparatus for vending merchand-

- dise, two compartments disposed end to end, the compartments having side entrances at their forward ends, and side exits at their rear ends, the exit at the rear of the forward 5 compartment being disposed at the entrance to the rear compartment, and there being another exit at the rear of the forward compartment into the rear compartment disposed at the junction of the exit of the forward 10 compartment and the entrance of the rear compartment, and watcher stations at the entrance of the forward compartment, at the exit of the rear compartment and at the junction of the exit of the forward compartment, the entrance of the rear compartment and the exit from the forward to the rear compartment.
3. In an apparatus for vending merchandise, two compartments disposed end to end, 20 the compartments having side entrances at their forward ends and side exits at their rear ends, the exit at the rear of the forward compartment being disposed at the entrance to the rear compartment, means to prevent 25 customers from entering the compartments at the exits and from leaving the compartments at the entrance, there being an additional exit at the rear of the forward compartment into the rear compartment disposed at the junction of the exit of the forward 30 compartment and the entrance of the rear compartment and means to prevent customers from passing directly to the rear compartment to the forward compartment, 35 through the exit leading from the forward compartment to the rear compartment.
4. An apparatus for vending merchandise, two compartments disposed adjacent each other, the compartments having entrances at their forward ends and exits at their rear ends, the exit at the rear of the forward compartments being disposed at the entrance to the rear compartments, means to prevent 40 customers from entering the compartments at the exits and from leaving the compartments at the entrances, there being an exit at the rear of the forward compartment into the rear compartment disposed at the junction of the exit of the forward 45 compartment and the entrance of the rear compartment, means to prevent customers from passing directly from the rear compartment to the forward compartment through the exit leaving from the forward compartment 50 to the rear compartment, and watcher stations at the entrance of the forward compartment, at the exit of the rear compartment, and at the junction of the exit of the forward compartment, the entrance to the rear compartment and the exit from the forward to the rear compartment.
5. An apparatus for vending merchandise, a plurality of sets of compartments, the compartments in each set being disposed side 55 by side and the sets of compartments being
- disposed in the rear of each other, there being entrances at the forward ends of the outer side walls of the compartments, and exits at the rear ends of the outer side walls of the compartment, each of the exits being disposed adjacent the entrance to a rear compartment, there being lateral passages at the ends of the compartments connecting the compartments in each set, and exits from the rear of the compartments into the adjacent rear compartments.
6. An apparatus for vending merchandise, a plurality of sets of compartments, the compartments in each set being disposed side by side and the sets of compartments being disposed in the rear of each other, there being entrances at the forward ends of the outer side walls of the compartments, and exits at the rear ends of the outer side walls of the compartment, each of the exits being disposed adjacent the entrance to a rear compartment, there being lateral passages at the ends of the compartments connecting the compartments in each set, and exits adjacent the lateral passages from the rear of the compartments into the adjacent rear compartments.
7. An apparatus for vending merchandise, a plurality of sets of compartments, the compartments in each set being disposed side by side and the sets of compartments being disposed in the rear of each other, there being entrances at the forward ends of the outer side walls of the compartments, and exits at the rear ends of the outer side walls of the compartment, each of the exits being disposed adjacent the entrance to a rear compartment, there being lateral passages at the ends of the compartments connecting the compartments in each set, and exists adjacent the lateral passages, and additional exits adjacent the junction of the exits at the rear of the forward compartments and the entrances at the forward ends of the rear compartments, the said exits adjacent the lateral 95 passages and the said junctions leading from the forward to the rear compartments.
8. In a self-service store, a plurality of sets of compartments, the compartments in each set being disposed side by side and the sets of compartments being disposed in the rear of each other, there being entrances at the forward ends of the outer side walls of the compartments, and exits at the rear ends of the outer side walls of the compartment, each of the exits being disposed adjacent the entrance to a rear compartment, there being lateral passages at the ends of the compartments connecting the compartments in each set, exits adjacent the lateral passages from the rear of the compartments into the adjacent rear compartments, and watcher stations at the junction of the exits of the forward compartments and the entrance of the rear compartments and at the junction of the lat- 100 105 110 115 120 125 130

eral passages with the exits leading to the rear compartments.

9. In a self-service store, a plurality of sets of compartments, the compartments in each set being disposed side by side and the sets of compartments being disposed in the rear of each other, there being entrances at the forward ends of the outer side walls of the compartments, and exits at the rear ends 10 of the outer side walls of the compartment, each of the exits being disposed adjacent the entrance to a rear compartment, there being lateral passages at the ends of the compartments connecting the compartments in each 15 set, exits from the rear of the compartments into the adjacent rear compartments, means to prevent customers from entering the compartments at the exits in the outer side walls and from leaving the compartments at the 20 entrances at the outer side walls, and additional means which prevents customers from passing from the rear to the forward compartments through exits leading from the forward to the rear compartments.
- 25 10. In a self-service store, a plurality of sets of compartments, the compartments in each set being disposed side by side and the

sets of compartments being disposed in the rear of each other, there being entrances at the forward ends of the outer side walls 30 of the compartments, and exits at the rear ends of the outer side walls of the compartment, each of the exits being disposed adjacent the entrance to a rear compartment, there being lateral passages at the ends of 35 the compartments connecting the compartments in each set, exits adjacent the lateral passages from the rear of the compartments into the adjacent rear compartments, and watcher stations at the junction of the exits 40 of the forward compartments and the entrance of the rear compartments and at the junction of the lateral passages with the exits leading to the rear compartments, means to prevent customers from entering the compartments at the exits in the outer side walls and from leaving the compartments at the 45 entrances at the outer side walls, and additional means which prevents customers from passing from the rear to the forward 50 compartments through exits leading from the forward to the rear compartments.

ALVA W. B. JOHNSON.
